H. C. SMART,
GAS BURNER FOR FURNACES,
APPLICATION FILED APR. 11, 1918.

1,288,450.

Patented Dec. 17, 1918.

INVENTOR,
Henry C. Smart
BY
Phillips Abbott.
ATTORNEY.

UNITED STATES PATENT OFFICE.

HENRY C. SMART, OF BROOKLYN, NEW YORK, ASSIGNOR TO STANDARD OIL COMPANY OF NEW YORK, OF NEW YORK, N. Y., A CORPORATION OF NEW YORK.

GAS-BURNER FOR FURNACES.

1,288,450.

Specification of Letters Patent. Patented Dec. 17, 1918.

Original application filed September 11, 1917, Serial No. 190,739. Divided and this application filed April 11, 1918. Serial No. 227,853.

To all whom it may concern:

Be it known that I, HENRY C. SMART, a citizen of the United States, and a resident in the borough of Brooklyn, county of 5 Kings, city and State of New York, have invented certain new and useful Improvements in Gas-Burners for Furnaces, of which the following is a specification, reference being had to the accompanying 10 drawings.

This application is a division of my former application Serial No. 190,739, filed September 11, 1917, for gas burners for use under stills, boilers, kettles and the like.

15 Generally stated, the purpose of this invention is to so construct the gas and air supplying and burning devices and to so correlate them with the setting of the boiler, still, or like structure in connection with 20 which they are used, that certain defects in former constructions may be obviated and increased efficiency secured; that is to say, by inclosing the air and gas supply pipes and their respective burner tubes and jets 25 within the brick work of the setting, they are sustained in their positions and protected against excessive heat, so that buckling and burning out of the gas and air pipes are largely prevented, and consequently 30 their durability greatly enhanced. Also more perfect admixture of the gas and air and more perfect distribution and control thereof are secured than heretofore.

In the drawings hereof I illustrate and 35 shall herein describe the invention as applied to a still adapted to oil distillation. I wish it to be understood, however, that my invention is adapted to gas burners used in furnaces generally under boilers, stills, 40 kettles, evaporators and the like.

In the drawings, Figure 1 is a horizontal sectional view of the brick setting of a still, showing the air and gas supply pipes and coöperating parts embedded therein, 45 the still itself, however, being omitted; Fig. 2 is a vertical sectional view on the line 2—2 of Fig. 1, showing diagrammatically the still or boiler in position; Fig. 3 is an enlarged plan view, partly in section, of cer-

tain details of the gas and air pipes and 50 their jets and burners; Fig. 4 is a sectional view of that which is shown in Fig. 3, taken on the line 4—4 of Fig. 3.

In the drawings 1 represents the brick work setting of the still, 2 the grate bars, 55 3 the bridge wall, 4 the filling plate, 5 the door, 6 the stack, 7 the combustion chamber. All these parts are, or may be of any preferred construction. The combustion chamber should, however, be on about the same 60 level as the grate bars, so that the heat generated by the burning gas may properly impinge on the boiler or still.

8, 8, are metallic air supply pipes closed at one end by suitable caps 9, and provided 65 with laterally disposed burner tubes 10. There are in the present instance seven such tubes connected with each of the pipes 8. There may be more or less, as preferred. In order that this part of the apparatus may 70 be more plainly understood, I represent at the upper part of Fig. 1 these devices as inclosed within the brickwork and at the lower part of the same figure I represent them as shown in full lines as though they 75 were exposed. It will be understood, however, that both the pipes 8 and preferably also the burner tubes 10 are embedded within the brickwork setting, so that they may be sustained and protected thereby and relatively cool therein.

11, 11, are two gas supply pipes located within the pipes 8. They are centered therein by centering screws 12, as shown best in Figs. 3 and 4. There may be as many of 85 these screws as desired and they may be spaced along the pipes as may be necessary to properly support and center the gas pipe and its jets relative to the air pipes and its burners. The gas supply pipes 11 are 90 provided with burner jets 13, which are so spaced upon the gas pipes that they register with the centers of the burner tubes 10. The jets are preferably not so long as the burner tubes, thus securing better admixture 95 of the gas and air. 14 is an air supply pipe which connects at each end with the air supply pipes 8, 8, and a branch 15 from

it may connect with a suitable blower or fan 16, which may be operated by a belt pulley 17, or in any other preferred manner.

The operation is as follows:

5 Coal, or its equivalent, is burned upon the grate bars in the ordinary way and the heat from that fire exerts its influence upon the forward part of the boiler or still, but a portion of the combustible material, solid and gaseous, thrown off by the burning coal, 10 is carried over the bridge wall 3 and into the combustion chamber 7, and were it not for the presence of the gas burners therein this material, or a part of it at least, would be apt to be carried through the combustion chamber without complete combustion and pass off through the stack and thus a part 15 of the heating properties of the fuel be lost. Under my improved construction and arrangement of the parts the gas enters from its source of supply through the pipes 11 and passes out through the jets 13 into the burner tubes 10, and at the same time air enters through the air supply pipes 8 and 20 mingles with the gas in the burner tubes 10; and in order that the proper admixture of air and gas may be secured, I prefer to regulate the supply of air by the employment of a suitable fan or blower 16, so that the 25 right proportion to coincide with the character and quality of the gas may be assured. Sometimes if the gas in its container is under requisite pressure, it will blow through the burner jets 13 into the burner tubes 10 30 in such manner as to cause them to operate on the principle of a Bunsen burner, since the jets will by their own suction draw in the requisite amount of air. It will be understood, therefore, that the proper mixture 35 of gas and air may be secured either by regulating the air supply, as by a blower, or by regulating the gas supply and its pressure.

40 The gas burned in the combustion chamber 7 as above stated, generates intense heat therein, through which the combustible material thrown off by the coal must necessarily pass on its way to the stack, so that not only is the gas itself completely consumed 45 but also all unconsumed products of combustion, solid and gaseous, which come over the bridge wall from the coal.

50 I have furthermore found that there is a preferred location for the gas burners within the combustion chamber; that is to say, they should occupy a position substantially equidistant from the bridge wall and the stack, because the products of combustion coming from the coal are usually deflected 55 upwardly by the bridge wall and coming in contact to a greater or less degree with the bottom of the boiler or still, will by it be deflected downwardly, and during the time 60 that these unconsumed products of combus-

tion are, so to speak in midair on their way 65 through the combustion chamber is when the burning gas can best attack them because then the flame can surround them completely, since they receive no protection either from the still bottom above or from the bottom of the combustion chamber below. In this way practically all the heat producing elements of the coal and of the gas are 70 beneficially employed and little if any, of it is lost up the stack.

75 Aside from the foregoing, certain additional and important advantages are secured by my invention, that is to say, in gas burners of the class here referred to, the gas and the air supply pipes and the jets and burner tubes therefor have usually been partially and in some instances entirely exposed in the bottom or at the sides of the combustion chamber, and consequently are subjected to great heat, so that after a time the heat 80 causes the pipes to buckle and burns them out, necessitating frequent renewal. Under my invention these relatively perishable parts are wholly embedded within and sustained and protected by the solid brickwork 85 of the setting and consequently are maintained in a condition of relative coolness, are not distorted and last a long time.

90 It will be obvious to those who are familiar with such matters that modifications 95 may be made in the details of construction without departing from the essentials of the invention. I therefore do not limit myself to the details shown and described.

I wish it to be understood that although 100 required to divide my said former application, I do not disclaim or abandon any patentable subject matter which may be disclosed but not claimed herein, because such 105 subject matter will, so far as may be permissible, be claimed in said former application.

I claim:

1. A gas burner for stills and the like embodying a continuous air supply pipe, which 110 extends as an unbroken pipe to the exterior of the still setting, burner tubes connected therewith, a gas supply pipe substantially co-extensive in length with the air supply pipe, jets shorter than the burner tubes connected 115 with the gas supply pipe and located respectively within the respective burner tubes, and adjustable centering devices located between the ends of the air supply pipe and supported by it and which support and center the gas supply pipe within the air supply pipe.

2. A gas burner for stills and the like embodying an air supply pipe, which extends as an unbroken pipe to the exterior of the 125 still setting, burner tubes connected therewith, a gas supply pipe substantially co-extensive in length with the air supply pipe

and located within it, jets shorter than the burner tubes connected with the gas supply pipe and located respectively within the respective burner tubes, adjustable centering devices located between the ends of the air supply pipe and which support and center

the gas supply pipe and the jets connected therewith, and means to regulate the supply of gas.

In testimony whereof I have signed my 10 name to this specification.

HENRY C. SMART.
